UNITED STATES PATENT OFFICE.

GEORGE DUNN, OF MIDDLETOWN, OHIO, ASSIGNOR OF ONE-HALF TO LOB-
DELL CAR WHEEL COMPANY, OF WILMINGTON, DELAWARE.

CALENDERING-ROLL.

SPECIFICATION forming part of Letters Patent No. 324,758, dated August 18, 1885.

Application filed March 30, 1885. (No model.)

To all whom it may concern:

Be it known that I, GEORGE DUNN, a citizen of the United States, and a resident of Middletown, Butler county, Ohio, have invented 5 certain Improvements in Calendering-Rolls, of which the following is a specification.

My invention consists of an improvement in calendering-rolls for paper-making, my improvement being designed to prevent wrinkling, cutting, or breaking of the paper web during the process of calendering.

The view in the accompanying drawing is an elevation of a set of calendering-rolls, the frame being shown in section.

15 A and A' are a series of calendering-rolls, the lowermost roll having journals adapted to bearings in the side frames, B, and above this are arranged a number of rolls, one over the other, to any desired number, the journals 20 of these rolls being guided in the vertical side frames, B. The uppermost roll, D, of the series constitutes the feed-roll, and around this roll and between it and the next one below, the paper enters the machine to be calendered.

25 As the paper is drawn into the calendering machine it is subjected to considerable strain, and unless the tension is perfectly uniform, and the paper has sufficient strength to stand the strain, it is apt to break in its 30 journey between the rolls. To prevent this breaking or wrinkling of the paper, and to provide for the requisite uniform tension, I construct the top roll, D, as shown in the drawing—that is, I make the roll at the extreme ends slightly greater in diameter than 35 throughout the rest of its intermediate length,

which corresponds with or exceeds the width of the paper to be acted on, so that this roll D rests on the next roll below only at its extreme ends, where what may be termed the "collars" d' are formed. The diameter of the intermediate portion, d, of this roll is only very little less than that of the collar d', so that when the paper is fed in between this lesser diameter of the upper roll and the next one 45 below, it will come into contact with the web of paper and give a certain tension to it, but will not nip it in the same way as if the roll were resting on the next one below throughout its entire length. Owing to this lesser diameter 50 there is a certain amount of lost motion, and the web of paper is drawn firmly back from the point where the first pinch of the roll draws the paper web into the calendering-rolls below under heavy pressure, and thus there is created a positive tension on the paper web in 55 close contact with the face of the second roll without injury of the sheet.

I claim as my invention—

A set of calendering-rolls provided with a feed-roll having its ends slightly larger in diameter than its intermediate portion over which the web of paper passes, substantially as and for the purpose set forth.

In testimony whereof I have signed my name to this specification in the presence of two subscribing witnesses.

GEORGE DUNN.
